US00D418602S

United States Patent [19]

Prokop et al.

[11] Patent Number: Des. 418,602

[45] Date of Patent: ** Jan. 4, 2000

[54] MEASURING INSTRUMENT FOR ANALYSIS OF BLOOD CONSTITUENTS

[75] Inventors: **Gary F. Prokop**, Wheaton; **Joshua P. Goldfarb**, Chicago; **Randall P. Bell**, River Forest, all of Ill.[73] Assignee: **Abbott Laboratories**, Abbott Park, Ill.

[**] Term: 14 Years

[21] Appl. No.: 29/065,597

[22] Filed: Jan. 24, 1997

[51] LOC (7) Cl. 24-02

[52] U.S. Cl. D24/169

[58] Field of Search D24/186, 231, D24/216, 232, 185, 167, 169; 606/181, 182, 185, 184; 422/56, 55, 73, 102; 128/770, 771, 635, 763

[57] CLAIM

We claim the ornamental design for a measuring instrument for analysis of blood constituents, as shown and described.

DESCRIPTION

FIG. 1 is a perspective view of a measuring instrument for analysis of blood constituents showing our new design.

FIG. 2 is a perspective view of a measuring instrument for analysis of blood constituents showing our new design, shown in open condition.

FIG. 3 is a front elevational view thereof;

FIG. 4 is a right side elevational view thereof;

FIG. 5 is a top view thereof;

FIG. 6 is a rear elevational view thereof;

FIG. 7 is a left side elevational view thereof; and,

FIG. 8 is a bottom view thereof.
